ELECTRIC LAMP SOCKET HOUSING

Morton Goldsholl, Highland Park, Ill., assignor to McGill Manufacturing Company, Inc., Valparaiso, Ind., a corporation of Indiana

Application July 26, 1954, Serial No. 31,602

Term of patent 14 years

(Cl. D48—4)

Fig. 1 is a side elevational view of an electric lamp socket housing showing my new design;

Fig. 2 is a front perspective view thereof;

Fig. 3 is a bottom plan view; and

Fig. 4 is a fragmentary cross-sectional view to a larger scale taken on the line 4—4 of Fig. 2.

The dotted lines shown in Figs. 1 and 3 are for illustrative purposes only.

I claim:

The ornamental design for an electric lamp socket housing, substantially as shown and described.
